UNITED STATES PATENT OFFICE.

ERNEST R. HUNTLEY, OF MILWAUKEE, WISCONSIN, ASSIGNOR TO INDUSTRIAL RESEARCH CORPORATION, OF TOLEDO, OHIO, A CORPORATION OF DELAWARE.

AIR CLEANER.

Application filed October 6, 1920. Serial No. 415,158.

This invention relates to improvements in apparatus for purifying gases, and particularly for separating therefrom solid substances such as dust, soot, ashes, etc., and 5 also for condensing vapors, for cooling air, for removing smoke, etc., by bringing the gases by means of centrifugal action into as intimate contact as possible with a washing fluid.

10 A particular object of my invention is to construct such an apparatus in which a rotating member is rotated by the current of gas drawn or blown through the apparatus.

Another object is to construct such an 15 apparatus in which a rotating member carries the liquid into contact with the gas, said member being rotated by the gas current drawn or blown through the apparatus.

Another object is to provide a liquid 20 container in which the level is maintained at a constant position by a float valve so that a uniform quantity of liquid is elevated by the rotating element.

Another object is to provide a more efficient, compact, and cheap construction than heretofore used.

Other objects will appear as I proceed with a more detailed description of that 25 particular embodiment of the invention which, for the purpose of illustration, I have shown in the appended drawings, in which similar numerals refer to similar parts throughout the several views.

Figure I represents a side elevation of the 30 gas washer, with parts broken away to show the internal structure.

Figure II is a vertical section on line 2—2 of Figure I.

Figure III is a view looking upward from 35 the bottom with the float chamber casing detached.

Figure IV is a section on line 4—4 of Figure I showing the air passages through the stationary vanes.

40 In the drawings the same reference numerals refer to the same parts throughout the several views.

1 represents the outer casing of the gas washer, which is suspended from the bracket 45 2 by screws 3, the bracket being attached to its support by screws 4. Casing 1 is provided at its center with a depending cylindrical portion 5 which has openings 6 at the top serving as air inlets. Rigidly mounted 50 within the lower part of the cylindrical por-

tion 5 is the set of stationary vanes 7 which are attached to the member 9. Member 9 is rigidly supported securely against a shoulder 11 within the cylinder 5 by the bolts 8 which depend from the spider 10 60 formed integral with casing 1 over the top of cylinder 5. Immediately below the stationary vanes 7 a set of impeller vanes 12 are rigidly mounted upon the rotary shaft 13, and are so designed that the entering gas 65 is directed by vanes 7 to impart a rapidly rotating motion to the impeller. The upper end of shaft 13 is carried by a bearing 14 in the spider 10 while near its lower end it is supported by a step ball bearing 15. 70 Mounted upon the lower end of shaft 13, such as by screw threads as shown in Figure II, is the outer conical member 16. The inner conical member 17 is rigidly mounted 75 upon the impeller 12, and the gas passing through the impeller vanes is thus directed through the narrow space between the two concentric conical members 16 and 17.

A detachable casing 18 which serves as the liquid reservoir is supported immediately 80 under casing 1 by means of the bail like member 19 which catches in the detent 20 in the bottom of the casing to retain the same in position. The liquid level is maintained at a predetermined position by means of a 85 float 23 and float valve 24 in the liquid supply pipe 25. The bottom of member 16 is formed into a downwardly extending cone 26 the tip of which extends below the liquid level. Surrounding the revolving cone 26 90 and spaced a short distance therefrom is a stationary cone shaped member 21 which is slightly flattened at the tip and contains therein an aperture 22 to allow the liquid to enter the space between members 21 and 26. 95 Cone member 21 is supported by an outwardly flaring base attached to the bottom of casing 1 by means of screw 29. The outwardly flaring base is provided with a series of openings 70 (see Figure III) to allow 100 the liquid to return to the reservoir.

In the operation of my device, the gas to be cleaned enters at the top through openings 6, and in passing through the stationary vanes 7 is directed against the vanes 105 of the impeller 12 and thus causes a rapid rotation of shaft 13 carrying the cone members 16 and 17 and the cone 26. Liquid is picked up by adhesion by the tip of cone 26 immersed therein and centrifugal force 110

causes the liquid film to pass up the surface of the cone and thence through the small openings 27 into the space between cone members 16 and 17 where the liquid film 5 comes in contact with the gas to be cleaned. Member 16 is provided with a downwardly and inwardly turned flange 28 just below openings 27 which serves to catch the liquid flying radially out and to direct the 10 same up through the holes 27. The liquid film now passes up along the inner surface of cone 16 and out over the top of cone 16 where it is sprayed horizontally against the casing 1 by the action of centrifugal 15 force. The gas in passing in a thin layer between the concentric cones 16 and 17 comes in intimate contact with the liquid film and thus its impurities may be taken up by the liquid. At the top of the cone the gas current is turned downward through the thin spray of liquid and here again the gas is washed free of its impurities or solid matter. The cleaned gas now passes downward under the lip 30 where it is given a sudden 20 change of direction and into the swelled passageway 31 and thence out through outlet 32. The liquid containing the impurities gravitates downward through the openings 70 and back into the reservoir 18 where the solid 25 impurities settle out. The reservoir is easily discharged whenever desired by swinging member 19 aside and withdrawing casing 18.

It should be observed that the velocity 30 of the air as it passes from the central cylinder 5 to the passageway 31 diminishes appreciably, due to the fact that the area of the passage through which the air is moving is considerably enlarged. This arises 40 from the fact that the cylinder 5 is more or less constricted, while adjacent the edge 30 of the casing 1, the air may pass at any point in the circumference thereof, and the speed therefore, is appreciably less. In 45 consequence, there is no important tendency to deflect the liquid falling from the edge of the cone 16 into the passage way 31.

This invention is intended particularly for cleaning air to be used in an internal 50 combustion engine. The air is then drawn through the cleaner by the suction of the engine. However it may be used for cleaning air for any other purpose and the air may be drawn through by any suction producing means, or it may be supplied under pressure to the cleaner.

I am aware that the particular embodiment of my invention above described and illustrated is susceptible of considerable variation without departing from the essence thereof and therefore I desire to claim the invention broadly as well as specifically as indicated by the appended claims.

I claim as my invention:

65 1. In a gas washer, a cleaning liquid res-

ervoir, an inverted rotatable cone having its apex dipping beneath the surface of said liquid, whereby a thin film of liquid is elevated along the outer surface of said cone by adhesion and centrifugal force, a rotatable hollow cone member, means for passing the liquid film from the outer surface of the first cone to the inner surface of said hollow cone, and means for passing the gas to be cleaned along the inner surface of said hollow cone. 70 75

2. In a gas washer, a cleaning liquid reservoir, an inverted rotatable cone having its apex dipping beneath the surface of said liquid, whereby a thin film of liquid is elevated along the outer surface of said cone by adhesion and centrifugal force, a rotatable hollow cone member, means for passing the liquid film from the outer surface of the first cone to the inner surface of said hollow cone, means for passing the gas to be cleaned along the inner surface of said hollow cone, and means for spraying the elevated liquid across the current of gas passing through the washer. 80 85 90

3. In an apparatus for subjecting gases to the action of liquids, a vessel for containing the liquid, a rotatable cone for elevating the liquid, a rotatable hollow cone member for receiving liquid from the elevator cone and for forming a film of liquid on its inner surface by centrifugal force, means for spraying said liquid film from said cone member, means for passing the uncleaned gas in intimate contact with said liquid film, and means for rotating said cone member by the current of gas passing through the apparatus. 95 100

4. A gas washer, comprising a liquid reservoir, a rotatable cone for elevating the liquid, a rotatable funnel shaped member for receiving liquid from the elevator cone and for forming a film of liquid on its inner surface by centrifugal force, means for passing the uncleaned gas in intimate contact with said film, and means for rotating said funnel shaped member by the velocity of the gas passing through the washer. 105 110 115

5. In a gas cleaning apparatus, the combination of a reservoir adapted to hold cleaning liquid; a rotatable member positioned above said reservoir and including a permanently inverted conical member adapted to rotate in the cleaning liquid and elevate same; and a hollow conical member the inner walls of which are adjacent and in prolongation of the outer wall of said inverted cone, whereby liquid lifted by the inverted cone is transferred to the inner wall of the inverted cone; and means for passing uncleaned gases in juxtaposition to said cleaning liquid. 120 125

6. In a gas cleaning apparatus, the combination of a reservoir adapted to hold cleaning liquid; a rotatable member positioned 130

- above said reservoir and including a permanently inverted conical member adapted to rotate in the cleaning liquid and elevate same; and a hollow conical member the inner 5 walls of which are adjacent and in prolongation of the outer wall of said inverted cone, whereby liquid lifted by the inverted cone is transferred to the inner wall of the inverted cone; means for spraying the cleaning liquid exteriorly of said hollow cone; and additional means for directing uncleaned 10 gases through said liquid spray.
7. In a gas cleaner, the combination of a chamber having a gas inlet and outlet; a rotatable member in said chamber for aiding the separation of foreign particles from gas passing through the cleaner, said member having a skirt attached to and rotatable therewith; means for conducting the incoming 15 gases over said rotatable member and passageways between the skirt and member whereby liquid is passed from the outside of the member to the inside of the skirt.
8. In a gas cleaner, the combination of a 20 chamber having a gas inlet and outlet; a rotatable member in said chamber for aiding the separation of foreign particles from gas passing through the cleaner, a skirt mounted on the periphery of said rotatable member and rotatable therewith; and means for conducting gases over said rotatable member and about the outer edge of said skirt whereby a reversal of direction of the incoming 25 gas current is brought about.
9. In a gas cleaning apparatus; the combination of a chamber having a gas inlet and outlet; a rotatable member in said chamber for aiding the separation of foreign particles from the gas passing through the apparatus, said member comprising a plurality 30 of gas deflecting blades, and a skirt expanding outwardly from said blades; stationary blades adjacent said rotatable blades; means for conducting incoming gases between said 35
- stationary and rotatable blades and around 40 the periphery of said skirt whereby said member is rotated; and a non-rotatable cup-shaped member with its edge positioned adjacent the periphery of said skirt about 45 which edge the incoming gases are adapted to have movement.
10. In a gas cleaning apparatus, the combination of a casing, a cup-shaped member in 50 said casing having a projecting side wall; an outlet port positioned adjacent the wall of said cup-shaped member; and a rotatable member positioned adjacent the edge of said cup-shaped member, said rotatable member including a plurality of radially extending 55 blades adapted to receive the impact of the incoming gases; and a skirt extending outwardly from said blades, the periphery of said skirt terminating adjacent the wall of said cup-shaped member; an inlet port adjacent the blades of the rotatable member; and 60 means for conducting gases from said inlet port between said blades and about said skirt to 65 said cup-shaped member.
11. In a gas cleaning apparatus, the combination of a casing having inlet and outlet 70 ports; a rotatable member within said casing having radial blades positioned thereupon and a skirt extending outwardly beyond the ends of said blades; stationary 75 blades adjacent said rotatable blades, and a non-rotatable cup-shaped member positioned within said casing, the wall of which being in juxtaposition with the periphery of said skirt; and means for conducting incoming 80 gases between said rotatable and stationary blades over the periphery of said skirt and about the edge of the wall of the cup-shaped member, the passing of the gases between the blades causing rotation of the rotatable member.

In testimony whereof, I affix my signature.

ERNEST R. HUNTLEY.
